UNITED STATES PATENT OFFICE.

VALENTINE H. HALLOCK, OF QUEENS, ASSIGNOR TO THE HALLOCK DAMPER REGULATOR COMPANY, OF BROOKLYN, NEW YORK.

DAMPER-REGULATOR FOR STEAM-BOILERS.

SPECIFICATION forming part of Letters Patent No. 276,810, dated May 1, 1883.

Application filed February 8, 1883. (No model.)

To all whom it may concern:

Be it known that I, VALENTINE H. HALLOCK, a citizen of the United States, residing at Queens, in the county of Queens and State 5 of New York, have invented new and useful Improvements in Damper-Regulators for Steam-Boilers, of which the following is a specification.

This invention relates to that class of damper-regulators for which Letters Patent of the United States were granted to me December 9, 1879, No. 222,489; and it consists in the novel means hereinafter described for guiding the piston-rod, whereby such rod may be considerably shortened and the height of space required to accommodate the apparatus is reduced to a minimum.

This invention is illustrated in the accompanying drawings, in which Figure 1 represents a front elevation, partly in section. Fig. 2 is a plan view, showing the connections of the damper. Fig. 3 is a cross-section on the line *x x*, Fig. 1, looking downward.

Similar letters indicate corresponding parts. The letter A designates a cylinder, which is connected with a water-chamber, B, and contains a piston, C, having its rod D arranged to extend upward through and beyond the top of the cylinder, where it connects with a weighted damper-operating cord or chain, E. The piston-rod, moreover, engages at the upper end with a cross-head, F, from which is suspended, by means of rods *o* and a second head, G, a weight, H, and when steam is admitted to the water-chamber B from the boiler the water is forced from such chamber into the cylinder, and acts on the piston C to lift it against the weight, thereby regulating the position of the damper.

For the purpose of insuring the correct operation of the apparatus I have found it important to provide the piston-rod D with a positive guide at the upper end, and before my present invention the guide was composed of

grooved rollers arranged in fixed bearings to receive the piston-rod between them, the rollers being placed at a distance above the head F equal to the movement of the piston. This guide was very effective in operation, but made it necessary to leave room above the rollers for the upward movement of the piston-rod and to comparatively elongate the rod for such movement, which, in some cases, was objectionable. To overcome such objection I provide the cross-head F with grooved rollers I, which engage with vertical guide-rods J, one to each rod, the rollers being mounted in the head on suitable axles. The guide-rods J extend upward from the top of the cylinder A a sufficient distance to allow the required movement of the cross-head F, together with the piston, they being secured at the opposite ends to brackets K, and as the cross-head moves up or down the rollers I travel along the guide-rods, whereby the piston-rod is steadied or guided in an effective manner. Thus, in lieu of the fixed guide heretofore used, I substitute a movable guide, and the result is that I require no space further than to permit the movement of the cross-head F, at the same time shortening the piston-rod to a material extent.

What I claim as new, and desire to secure by Letters Patent, is—

The combination, substantially as hereinbefore set forth, with the cylinder, the piston, and the piston-rod connecting with the weighted damper-operating cord or chain, of the weighted cross-head F, engaging the piston-rod, the guide-rods J, and the grooved rollers I, mounted in the cross-head to engage the guide-rods, for the purpose specified.

In testimony whereof I have hereunto set my hand and seal in the presence of two subscribing witnesses.

VALENTINE H. HALLOCK. [L.S.]
